ELECTRICAL CONTROLLING APPARATUS

John D. Russell, Franklin, Pa., assignor to Joy
Manufacturing Company, Pittsburgh, Pa., a
corporation of Pennsylvania

Application May 1, 1948, Serial No. 24,622

20 Claims. (Cl. 201—48)

1

My invention relates to electrical controlling apparatus, and more particularly to motor reversing apparatus having means for preventing destructive arcing.

An object of my invention is to provide an improved motor reversing apparatus. Another object is to provide an improved motor reversing apparatus for preventing arcing. Still another object is to provide an improved motor reversing apparatus associated with a motor having a pilot circuit and including means for interrupting the pilot circuit before the reverse switch elements receive any movement. A further object is to provide an improved reversing apparatus having improved means for eliminating arcing. Still a further object of my invention is to provide an improved motor controlling and reversing apparatus having separate control elements for respectively separating and moving to different relations for reverse operation, the contact elements of a reverse switch. Yet another object of my invention is to provide an improved reverse switch mechanism having separate control elements one for separating reverse switch contacts and another for changing their relative positions to effect reverse operation, with means coacting with said elements to hold said second element until the first element has effected the separation it is adapted to accomplish. Other objects and advantages of the invention will hereinafter more fully appear.

In the accompanying drawings, in which one illustrative embodiment of my invention is shown for purposes of illustration,

Fig. 1 is a wiring diagram showing the controlling apparatus of the invention in use in a simple circuit.

Fig. 2 is an end view, the pilot switch end view, of the controlling apparatus.

Fig. 3 is a longitudinal sectional view on the plane of the line 3—3 of Fig. 2.

Fig. 4 is a similar view showing the parts in a different position, a position with the pilot circuit broken and connections for resistance arc elimination effected.

Fig. 5 is a view similar to Figs. 3 and 4, showing the parts in still a different position with the movable reverse switch contacts separated from the relatively stationary contacts and the parts in position for effecting a reversal of the motor connections.

Fig. 6 is a transverse section on the plane of the line 6—6 of Fig. 3.

Fig. 7 is a transverse section on the plane of the line 7—7 of Fig. 3.

2

Fig. 8 is a view similar to Fig. 6 showing the parts in a different position.

Fig. 9 is a view similar to Fig. 7 showing the parts in a different position.

Fig. 10 is a transverse sectional view on the plane of the line 10—10 of Fig. 3.

For the purpose of illustrating the invention in use, I have shown in Fig. 1 a very much simplified wiring diagram showing the control system for a direct current motor of such size that the progressive cutting out of resistance during motor starting is unnecessary, and I have omitted certain conventional protective devices, such as overload protection means, to keep the drawing as simple as possible.

The power lines 1 and 2 are connectible respectively with conductors 3 and 4 by switch elements 5 and 6 which are connected for movement together by an appropriate connecting element 7 of insulating material. An armature 8 is adapted under force exerted thereon by a solenoid 9 to control the movement of the switch including the parts 5, 6 and 7, which switch may be characterized as a main line switch. The conductor 3 is connected to the series field 11 of a motor 12, and also to the shunt field 13 of such motor. The armature of the motor 12 is designated 14, and has associated with it a commutating winding 15. A conductor 16 connects the shunt field to the conductor 4. At 18 there is diagrammatically shown in Fig. 1 the reverse switch mechanism which constitutes the subject matter of this application. It will be observed that this has a contact 20 connected to the conductor 4; another contact 21 connected by a conductor 22 to the end of the series field which is not connected to the conductor 3; a contact 23 connected to the commutating winding 15; and a contact 24 connected by a conductor 25, through appropriate brush means, with the armature 14. A pilot switch element 26, ringlike in shape and constituting a conductor and contact element and forming a portion of the apparatus later more fully described in detail, is adapted to connect stationary contacts 27 and 28, of which 27 is connected by a conductor 29 to one end of the solenoid 9, while 28 is connected by a conductor 30 to the power line 1. The other end of the solenoid 9 is connected to a conductor 31 between which and a further conductor 32 connected to the power line 2 there are arranged a suitable starting switch 33 and a suitable stop switch 34, both illustrated as of the push button type. These switches are connected by a conductor 35 which is connected in turn by a con-

ductor 36 to a contact element 37 which is connectible by a movable contact 38 with another contact element 39 connected as at 40 to the conductor 31. The contact element 38 is connected by a suitable non-conducting element 41 with the solenoid 9.

The mode of operation of this structure will be understood without extensive description. Upon closing movement of the starting push button 33 a circuit will be established from power line 2 through conductor 32, stop switch 34, conductor 35, start switch 33, conductor 31, solenoid 9, conductor 29, then-closed pilot switch 27, 26, 28, and conductor 30 back to the power line 1. When the main line switch is moved to closed position, the interlock 33 will move with it and establish a holding circuit through the solenoid 9 and by which the starting push button switch 33 and by which the starting push button switch 33 and by which a portion of the conductor 31 will be shunted by the conductor 36, interlock switch 37, 38, 39 and the conductor 40. Then, until the stop switch 34 is opened, with the structure illustrated, the main line switch will be maintained closed even though the switch 33 is allowed to open. On closure of the main line switch, the motor 12 will operate in one direction or the other, depending upon the position of the reverse switch mechanism 18, the different positions of this reverse switch being effective selectively to connect contacts 20 and 23 and contacts 24 and 21 to effect motor rotation in one direction, and contacts 20 and 24 and contacts 23 and 21 to effect motor rotation in the other direction. Whenever the reverse switch is to be moved, the pilot switch 26 will be opened, as will later be understood, resulting in breaking the circuit through the solenoid 9 and movement to open position of the main line contacts 5 and 6.

Now turning more particularly to Figs. 2 to 10 inclusive, it will be observed that the improved controlling apparatus therein disclosed includes a casing 50 providing a chamber 51 therein and having spaced from its shell by a series of insulating spools 53 a plate of insulating material 54. The plate 54 and spools 53 are held to the shell 50 by screws 52. The plate 54 carries suitably fixed with respect to it, and herein indicated as constructed integrally with it, a series of four socket-like members 55A, 55B, 55C and 55D, each of said socket members having formed therein a bore 56 with which there communicates an opening 57 of smaller diameter extending through the plate member 54. Yieldably supported in each of the bores 56 is a contact element 58, these contact elements being respectively designated K1, K2, K3, and K4. Each of these contact members K1, K2, K3 and K4 includes a stem portion 61 having a connector device 62 for securing a conductor to it at one end of it and a cupped, herein generally conically bored, contact element proper 63, the bore of which is designated 64. The contact elements K1, K2, K3 and K4 may be regarded as the relatively stationary contacts in that they are stationary except for their yielding mountings, and it will be understood that these contact elements may, in the order mentioned, be considered to be connected, for illustration, to the conductor 4, to the commutating winding 15, to the conductor 22, and to the conductor 25.

There are four movable contacts adapted to cooperate with the stationary contacts K1, K2, K3 and K4 to effect motor reversal, and these movable contacts are respectively designated C1, C2, C3, and C4. Each has a conical contact sur-

face 65, and each is held by a threaded stud portion 66 and a nut 67 to an insulating plate 68. The contacts C1 and C4 are connected with each other by a conductor bar 69, and the contacts C2 and C3 are connected together by a conductor bar 70, the conductor bars being clamped between the contact portions of the contact elements and the insulating plate 68. It may be noted that the stationary contacts and the movable contacts are each disposed at the corners of a square.

The movable contacts C1, C2, C3 and C4 and their conductor bars are adapted to connect the relatively stationary contacts K1 and K2 and the relatively stationary contacts K3 and K4 to effect motor rotation in one direction, and to connect the contacts K1 and K4 and the contacts K2 and K3, in a 90° turned position of the plate 68, to effect reverse operation of the motor.

The plate 54 also has secured to it by suitable clamping and conductor attaching devices 71, resilient conductor elements 72 and 73 which respectively carry at their free ends the contact elements 27 and 28. The plate 54 is cut away at its center to provide a cylindrical opening 75 into which at diametrically oppositely spaced points the resilient conductor elements 72 and 73 project, and the conductor element 26, which is herein of annular form, carries four contact buttons 77, each spaced 90° from those at opposite sides of it, for engagement with the stationary contacts 27 and 28. This results in a connection of the contact elements 27 and 28 in each of the different, 90° apart, circuit closing positions of the reverse switch mechanism; and to improve durability the contact buttons 77 are provided, so that the pilot circuit may be broken by contact elements of suitable material, such as silver, or other arc resistant material.

The plate 68 has a central opening 80 formed through it surrounded by a projecting annular wall 81 of the same internal contour as the opening 80. From the other side of the plate 68 there extends an annular wall 82 surrounding a recess of larger diameter than the opening 80 and leaving an annular shoulder 83 surrounding such opening 80 for engagement by a spring 84 whose opposite end rests against the internal wall of the casing 50. The casing 50 has an opening 85 formed therein surrounded at its inner end by a projecting collar-like portion 86 which supports the spring 84 against lateral displacement. A tubular operating element 90 extends through the opening 85 and at its portion received in said opening is cylindrical in cross section, whereby it is freely rotatable in such opening. This member 90 has an enlarged inner end 91 which is polygonal—herein shown as hexagonal, in external form so as to be slidable but non-rotatable relatively to wall 81, which is also hexagonal—and there is a shoulder 92 at the outer end of the enlarged portion 91 which coacts with the end of the collar-like portion 86. The shaft 90 is rotatable by a handle device 93, which includes a portion 94 non-rotatably secured to the shaft and having arm portions 95 supporting a pivot 96 on which the stirrup-like portion 97 of an operating handle or lever 98 is pivotally mounted. The operating handle proper 99 may, except as restricted as hereinafter explained, be swung outwardly and inwardly about the axis of the pivot pin 96 and may be utilized to turn the shaft 90 and the parts which are turnable with that shaft. The stirrup portion 97 has an outwardly projecting nose 100 which normally lies within the annular wall 101 of a

rotatable hand wheel element 102 which is mounted upon a stem 103 received in a bore 104 within the shaft 90, the hand wheel 102 being fixed to the stem 103 as at 105 so as to insure rotation of the latter with the hand wheel. At the inner end thereof, the bore 104 is internally threaded as at 107 and may be also slightly enlarged, if desired. The stem 103 has, in a position to cooperate with the threaded portion 107, an enlarged externally threaded portion 108, and inwardly of the portion 108 there is a reduced stem portion 109 having a stop element 110 secured to its innermost end. A deeply dished carrier element 112, of insulating material, is supported as at 113 for sliding movement on the stem portion 109, and a spring 114 is arranged between the inner end of the member 112 and the stop collar 110. The interior of the deeply dished member 112 is similar in cross section to the shape of wall 81—here shown hexagonal—in order to be slideable but non-rotatable relatively to wall 81 and member 68. The outer periphery of this member 112 is in the form of a flange 115 having mutually opposite ears 116 projecting therefrom. A high resistance element R of annular form but with projecting ears R1 and R2 is secured to the member 112, with the ears R1 and R2 thereof overlying the ears 116 of the member 112. It will be observed that the ears R1 and R2 are in such relation to the bars 69 and 70 that the resistance element is adapted to connect the bars 69 and 70 after the main line switch has been opened, thereby to bring the motor to a stop by short-circuiting its rotor through the high resistance element R.

The switch element 26 is supported by holding elements 118 extending through the resistance element R and through the flange 115 and surrounded by spacing sleeves 119 and springs 120. The spacing sleeves are short enough so that there is possible a substantial amount of yield of the contact element 26 longitudinally of the holding elements 118, and longitudinally also of the axis of rotation of the reverse switch. A spring 121 is provided between the shoulder 45 which surrounds the reduced stem portion 109 and the bottom of the recess in the member 112.

To recapitulate, reversing is controlled by the lever 98 which turns a hollow shaft 90 with which the support member 68 is slidably connected while being held against relative rotation. The support member 112 is slideable relative to the member 68 but held against rotation with respect to it. The inner member 103, turnable by the hand wheel 102, is adjustable longitudinally of the hollow shaft 90 by the screw thread arrangement previously described. It is adapted to move the support member 112 and through the latter, when the resistance member R has engaged the bars 69 and 70, the support member 68 also. The sleeve portion 81 of the member 68, it will be remembered, is polygonal, herein shown as hexagonal exteriorly, and the recess in the deeply dished support member 112 is also correspondingly polygonal in cross section, with the result that when the shaft 90 rotates, it turns with it the support member 68 and that support member turns with it the support member 112. Due to the presence of the sleeve 114', movement outwardly of the member 103 a short distance—a distance sufficient to effect separation of the contacts 71 from the contacts 27 and 28—will cause the member 112 to be picked up by the outwardly moving member 103 and moved from the position shown in 73

Fig. 3 to the position shown in Fig. 5, that is, moved to a position to cause the resistance element R to engage the conductor bars 69 and 70. Then a very short further outward movement of the support 112 will cause the picking up of the support element 68 and the movement of the contacts C1, C2, C3 and C4 out of cooperative relation with the contacts K1, K2, K3 and K4, the spring 84 yielding to permit this to occur. It will be noted that the contacts K1, K2, K3 and K4 can move only a short distance before the members 62 engage the member 54. When extreme outward movement of the element 103 occurs, the parts will occupy the relative positions shown in Fig. 5, and it will be noted that the lever 98 may, since the annular wall 101 will no longer obstruct movement of the projection 100, be swung outwardly to the dotted line position shown in Fig. 5, and thus move out of a notch 123 in a notched arcuate rib 124 until it overlies another notch 125 a quadrant away from the notch 123, and it may then be swung into that notch after having positioned the movable contacts C1, C2, C3 and C4 so that they will establish connections for reverse operation of the motor.

Before describing the general mode of operation of the apparatus, it will be noted that when the hand wheel 102 is rotated in a direction to move the shaft 103 to the left in Fig. 3, the spring 114 will be the first one to yield, and the spacing sleeve 114' will come up against the base of the carrier element 112 and move this element and when the heads 113 move up against the member 26 the pilot circuit will be opened. When the member 26 exerts pressure through the spacing sleeves 119 on the member 112, that member will move relative to the member 68 until the resistance arc member R is brought against the contact bars 69 and 70. When this engagement occurs, further rotation of the hand wheel 102 will cause the member 68 to move to the left in Fig. 3 and pull the conical contact elements C1, C2, C3 and C4 out of the socketed contact elements K1, K2, K3 and K4 to some position such as shown in Fig. 5. Fig. 5 well shows the result of these operations. It will be noted that the spring 114 is compressed and that the sleeve 114' extends solidly between the stop member 110 and the member 112. It will be noted that the elements 115 have pulled the switch element 26 firmly up against the sleeves 119. It will be observed that the resistance element R is held firmly against the conductor bar 70, and it is also against the bar 69. Finally, it will be noted that through the contact between the resistance element R and the bars 69 and 70, the support member 68 has been moved to move the contact elements C1, etc. out of the sockets 64. When the hand wheel 102 is turned in the opposite direction and the parts move toward the right, the first thing that will occur will be the seating of the contacts C1, etc. in the recessed contact elements K1, etc. Then the resistance element R will leave its position of engagement with the bars 69 and 70. Then the contacts 71 carried by the contact element 26 will engage the contacts 27 and 28. Further movement of the hand wheel 102 will cause the sleeve 114' to exert a pressure on the member 112, and it, through the springs 120, will press the contact element 26 in a manner to press the contacts 71 against the contacts 27 and 28, but over-turning of the hand wheel 102 can cause no breakage. The mode of

operation of the invention may now be summarized.

When the motor 12 is running in one direction, the parts may all be in the relative positions shown in Fig. 3. The pilot circuit is closed between the contacts 27, 28 by the contact ring 26 and its contact elements 71. The resistor element R is spaced from the conductor bars 69 and 70 on the reverse switch. The conical contacts C1, C2, C3 and C4 of the reverse switch are 10 yieldingly but firmly pressed by force exerted by the spring 84 into the yieldingly mounted contacts K1, K2, K3 and K4. The lever 98 cannot be swung because the position of the hand wheel prevents its being lifted out of the notch 123.

If it now be desired to stop the motor 12 and to reverse it, the hand wheel 102 will be turned in a direction to move the member 103 outwardly, that is toward the left in Fig. 3. The spring 114 will be slightly compressed and then, through the pacing sleeve 114', the support member 112 will be started to move to the left, and as soon as this motion progresses far enough to cause the heads of the bolts 118 to engage the contact ring 26, this contact ring will be moved out to separate the contacts 71 from the stationary contacts 27 and 28, and the circuit through the solenoid 9 will be opened and the main line contactors 5 and 6 will drop open and current supply to the motor will be interrupted. Further rotation of the hand wheel 102 to move the member 103 still further to the left will bring the high resistance element R into contact with the bars 69 and 70 and short-circuit the motor armature through the high resistance of the member R and thus effect dynamic braking. The motor may probably have slowed down somewhat during the period between opening of the main line switch and contact by the resistance element R of the conductor bars 69, 70. Further movement of the hand wheel 102 in a direction to move the member 103 to the left will cause lifting of the contacts C1, C2, C3 and C4 out of the yieldably mounted contacts with which they have been engaged. Only after this movement has proceeded to such an extent that it is possible to rotate the member 68 without interference between the movable contacts C1, C2, C3 and C4 and the stationary contacts K1, K2, K3 and K4 can the lever 98 be lifted far enough out of the notch 121 to rotate the hollow shaft 90, support member 68 and support member 112. When this rotary movement is possible, lever 98 can be swung about the axis of the shaft 96, counter-clockwise in Fig. 3, and then moved, counter-clockwise in Fig. 6, about the horizontal axis of rotation of the shaft 90 to effect the establishment, through the rotation of that shaft, of a positioning of contacts C1, C2, C3 and C4 for reverse motor connections. Premature swing of the lever 98 is prevented by the cooperation of the extension 100 with the inner wall 101 of the hand wheel 102. When the position of the contacts C1, C2, C3 and C4 has been changed, to align them with the contacts K1, K2, K3 and K4, in a proper manner for the establishment of reverse operation of the motor, the lever 98 will be latched in the notch 125 and the hand wheel 102 may be turned in a direction to move the member 103 to the right in Fig. 3. This will first permit the spring 84 to effect contact-establishing relation between the contact elements C1, C2, C3 and C4 with the proper one of contact elements K1, K2, K3 and K4. It will next permit separation of the resistor element R from

the bars 69 and 70, and finally will permit contacts 71 on the ring 26 to engage contacts 27 and 28 and thereby close the pilot circuit with the result that the motor can again be set in operation, but in a reverse direction, by the closure of the starting switch 33. Desirably current supply to the motor may be interrupted by opening of the stop switch before the handwheel 102 will be turned, but this is obviously not imperative, as the switch 26 controls the same circuit.

While there is in this application specifically described one form which my invention may assume in practice, it will be understood that this form of the invention is shown for purposes of illustration and that the invention may be modified and embodied in various other forms without departing from its spirit or the scope of the appended claims.

What I claim as new and desire to secure by Letters Patent is:

1. In an apparatus of the character described, in combination, a reverse switch including movable contacts and contacts with which said movable contacts cooperate in effecting a reversing function, a high resistance element, and means for moving said resistance element and said movable contacts requiring interconnection of said movable contacts through said resistance element as a prerequisite to the opening of the circuit between said movable contacts and the reverse switch contacts with which they cooperate.
2. In an apparatus of the character described, in combination, a reverse switch including movable contacts and contacts with which said movable contacts cooperate in effecting a reversing function, a high resistance element, and means including a lost motion connection between said resistance element and said movable contacts for moving said resistance element and said movable contacts requiring interconnection of said movable contacts through said resistance element as a prerequisite to the opening of the circuit between said movable contacts and the reverse switch contacts with which they cooperate.
3. In an apparatus of the character described, in combination, a reverse switch including movable contacts and contacts with which said movable contacts cooperate in effecting a reversing function, means for supporting said movable contacts for rotary movement and for movement at right angles to the planes of such rotary movement, a high resistance element, and means for moving said resistance element and said movable contacts at right angles to such planes of rotary movement requiring the interconnection of said movable contacts through said resistance element as a prerequisite to the opening of a circuit between said movable contacts and the reverse switch contacts with which they cooperate.
4. In an apparatus of the character described, in combination, a reverse switch including movable contacts and contacts with which said movable contacts cooperate in effecting a reversing function, high resistance means, and means for short-circuiting one of said sets of contacts through said high resistance means as a prerequisite to the opening of a circuit by the separation of said movable contacts from the reverse switch contacts with which they cooperate.
5. In an apparatus of the character described, in combination, a reverse switch including mov-

able contacts and contacts with which said movable contacts cooperate in effecting a reversing function, high resistance means, means for supporting the same for bodily movement, and means for bodily moving said high resistance means for short-circuiting one of said sets of contacts through said resistance means as a prerequisite to the opening of a circuit by the separation of said movable contacts from the reverse switch contacts with which they cooperate.

6. In an apparatus of the character described, in combination, a reverse switch including movable contacts and contacts with which said movable contacts cooperate in effecting a reversing function, high resistance means, connections between said movable contacts in pairs, and means for electrically connecting said connections between said movable contacts through said high resistance means as a prerequisite to the opening of a circuit by the separation of said movable contacts from the reverse switch contacts with which they cooperate.

7. In an apparatus of the character described, a pilot switch including at least one stationary contact and a relatively movable contact adapted to be moved between positions in which it respectively engages and is separated from said at least stationary contact, a reverse switch including a set of relatively stationary contacts and a cooperating set of relatively movable contacts, a movably supported, high resistance, short-circuiting contact, and means for controlling said several movable contacts in a predetermined sequence, first moving said first movable contact to open circuit position, then moving said short-circuiting contact to interconnect said set of relatively movable contacts, and finally moving said cooperating set of relatively movable contacts to open circuit position.

8. In an apparatus of the character described, a pilot switch including stationary contacts and a relatively movable contact adapted to be moved between positions in which it respectively engages and is separated from said contacts, a reverse switch including a second set of relatively stationary contacts and a cooperating set of relatively movable contacts, a movably supported, high resistance, short-circuiting contact, and means for controlling said several movable contacts in a predetermined sequence, first moving said first movable contact to open circuit position, then moving said short-circuiting contact to interconnect said set of relatively movable contacts, and finally moving said cooperating set of relatively movable contacts to open circuit position, said several movable contacts all movable in a common direction in the foregoing movements thereof.

9. In an apparatus of the character described, a pilot switch including stationary contacts and a relatively movable contact adapted to be moved between positions in which it respectively engages and is separated from said contacts, a reverse switch including a second set of relatively stationary contacts and a cooperating set of relatively movable contacts, a movably supported, high resistance, short-circuiting contact, and means for controlling said several movable contacts in a predetermined sequence, first moving said first movable contact to open circuit position, then moving said short-circuiting contact to interconnect said set of relatively movable contacts, and finally moving said cooperating set of relatively movable contacts to open circuit position, said controlling means including an element

yieldingly supporting said first movable contact and carrying said short-circuiting contact.

10. In a reverse switch, a shaft, support means slidably supported on said shaft but fixed against rotation relative to the latter, reverse switch contacts carried by said support means, relatively stationary reverse switch contacts, a handle mounted on said shaft for swinging about an axis disposed transversely to the axis of said shaft, means for holding said handle against rotation about the axis of said shaft when in predetermined angular relation to said shaft, a second shaft coaxial with said first mentioned shaft and having a connection with the latter operative on relative rotation of the second shaft with respect to the first shaft to effect movement of said second shaft axially of said first shaft, means for rotating said second mentioned shaft axially of said first shaft, means for holding said handle engaged by said handle holding means, a pilot switch arranged for opening by said second mentioned shaft, and means movable by said second mentioned shaft for moving said first mentioned reverse switch contacts axially of said first shaft to open circuit position before the rotating means for said second mentioned shaft releases the handle of said first mentioned shaft for rotation.

11. In a reverse switch, a hollow shaft, support means slidably supported on said shaft but fixed against rotation relative to the latter, reverse switch contacts carried by said support means, relatively stationary reverse switch contacts, a handle pivot member secured to said shaft, a handle mounted on said pivot member for swinging about an axis disposed transversely to the axis of said shaft, means for holding said handle against rotation about the axis of said shaft when in predetermined angular relation to said shaft, a second shaft coaxial with said first mentioned shaft and having a connection with the latter operative on relative rotation of the second shaft with respect to the first shaft to effect movement of said second shaft axially within said first shaft, means for rotating said second mentioned shaft operative except in certain predetermined relative axial positions between said shafts to hold said handle engaged by said handle holding means, a pilot switch arranged for opening by said second mentioned shaft, and means movable by said second mentioned shaft for moving said first mentioned reverse switch contacts axially of said first shaft to open circuit position before the rotating means for said second mentioned shaft releases the handle of said first mentioned shaft for rotation.

12. In a reverse switch, a hollow shaft, support means slidably supported on said shaft but fixed against rotation relative to the latter, reverse switch contacts carried by said support means, relatively stationary reverse switch contacts, a handle pivot member secured to said shaft, a handle mounted on said pivot member for swinging about an axis disposed transversely to the axis of said shaft, a notched rib for holding said handle against rotation about the axis of said shaft when in predetermined angular relation to said shaft, a second shaft coaxial with said first mentioned shaft and having a connection with the latter operative on relative rotation of the second shaft with respect to the first shaft to effect movement of said second shaft axially within said first shaft, means for rotating said second mentioned shaft operative except in certain predetermined relative axial positions between said

shafts to hold said handle in the notches in said rib, a pilot switch arranged for opening by said second mentioned shaft, and means movable by said second mentioned shaft for moving said first mentioned reverse switch contacts axially of said first shaft to open circuit position before the rotating means for said second mentioned shaft releases the handle of said first mentioned shaft for rotation.

13. In a reverse switch, a shaft, support means slidably supported on said shaft but fixed against rotation relative to the latter, reverse switch contacts carried by said support means, relatively stationary reverse switch contacts, a handle mounted on said shaft for swinging about an axis disposed transversely to the axis of said shaft, projections for holding said handle against rotation about the axis of said shaft when in predetermined angular relation to said shaft, a second shaft coaxial with said first mentioned shaft and having a connection with the latter operative on relative rotation of the second shaft with respect to the first shaft to effect movement of said second shaft axially of said first shaft, means for rotating said second mentioned shaft operative except in certain predetermined relative axial positions between said shafts to hold said handle against release from said projections, a pilot switch arranged for opening by said second mentioned shaft, and means movable by said second mentioned shaft for moving said first mentioned reverse switch contacts axially of said first shaft to open circuit position before the rotating means for said second mentioned shaft releases the handle of said first mentioned shaft for movement out of constraint by said projections.

14. In combination, means forming a casing, relatively stationary reverse contacts carried by said casing, relatively stationary pilot contacts carried by said casing, said contacts arranged symmetrically with respect to an axis extending through said casing, two shafts having their centers in the same line with said axis, means for effecting rotation of each of said shafts, means for effecting relative axial movement between said shafts upon rotation of one of said shafts relative to the other, a member slidably supported on one of said shafts, a member slidably supported on the other of said shafts, said members having portions in telescoping relation with respect to each other, said telescoping portions formed to prevent rotation between said members, a pilot switch element yieldingly connected to one of said members, reverse switch contacts and conductor bars fixed to the other of said members, and a high resistance element carried by said member which carries a pilot switch element and engageable in a predetermined relative position between said members with said conductor bars.

15. In combination, means forming a casing, relatively stationary reverse contacts carried by said casing, relatively stationary pilot contacts carried by said casing, said contacts arranged symmetrically with respect to an axis extending through said casing, two shafts having their centers in the same line with said axis, means for effecting rotation of each of said shafts, means for effecting relative axial movement between said shafts upon rotation of one of said shafts relative to the other, a member slidably supported on one of said shafts, a member slidably supported on the other of said shafts, said members having portions in telescoping relation with respect to each other, said telescoping portions

formed to prevent rotation between said members, a pilot switch element yieldingly connected to one of said members, reverse switch contacts and conductor bars fixed to the other of said members, and a high resistance element carried by said member which carries a pilot switch element and engageable in a predetermined relative position between said members with said conductor bars, said shaft rotating means including members rotating with each of said shafts and one having a projection and the other a cooperating rim.

16. In a switch mechanism, in combination, means forming a casing, at least one stationary pilot switch element carried by the casing, reverse switch elements carried by the casing, reverse switch elements relatively movable with respect to said first mentioned reverse switch elements, supporting means for said relatively movable reverse switch contact elements, a support member movable bodily relative to said supporting means but held against relative rotation with respect to the latter, at least one pilot switch element carried by said support member, contact bars mounted on said supporting means and connecting certain of said movable contact elements, and a high resistance element for establishing a high resistance circuit between said bars carried by said support member and movable by the latter into contact with said bars when said support member is in a position with said pilot circuit switch elements out of contact with each other.

17. In an apparatus of the character described, means forming a casing having a chamber therein and having an end plate, pilot switch contacts supported by said end plate, recessed reverse switch contacts supported by said end plate, coaxial shafts rotatably supported by said casing, one of said shafts confined against axial movement and the other being axially movable and having associated with it means for effecting its axial movement upon rotation thereof, a plurality of support members telescopically arranged with respect to each other and to said shaft which is rotatable only and having means for preventing relative rotation with respect to each other and to said shaft which is rotatable only, a pilot switch element yieldingly connected to one of said support members, reverse contacts carried by the other of said support members, means for yieldingly pressing said last mentioned reverse contacts towards said recessed reverse contacts, and means movable with said pilot switch element carrying support member for moving said other support member to move the reverse contacts which the latter supports out of engagement with the recessed reverse switch contacts, under the thrust of said other support member.

18. In an apparatus of the character described, in combination, a casing, a rotating shaft supported in said casing, another shaft movable axially within said first mentioned shaft, means for rotating said first mentioned shaft, means for moving said second mentioned shaft axially relative to said first mentioned shaft, means for preventing rotation of said first mentioned shaft except when said second mentioned shaft occupies a predetermined longitudinal relation with respect to said first mentioned shaft, a pilot switch movable between open and closed positions by said second mentioned shaft, reverse contacts rotatable by rotation of said first mentioned shaft, and means for moving said reverse contacts axially of said casing to open circuit position during

movement of said second mentioned shaft to said predetermined position.

19. In an apparatus of the character described, in combination, a casing, a rotating shaft supported in said casing, another shaft movable axially of said first mentioned shaft, means for rotating said first mentioned shaft, means for moving said second mentioned shaft axially relative to said first mentioned shaft, means for preventing rotation of said first mentioned shaft except when said second mentioned shaft occupies a predetermined longitudinal relation with respect to said first mentioned shaft, a pilot switch movable between open and closed positions by said second mentioned shaft, reverse contacts rotatable by rotation of said first mentioned shaft, and means actuated by said second mentioned shaft for moving said reverse contacts axially of said casing to open circuit position during movement of said second mentioned shaft to said predetermined position.

20. In an electrical controlling apparatus, in combination, means forming a casing, relatively stationary pilot contacts supported by said casing, relatively stationary reverse switch contacts
